DOOR CHECK

Frederick J. Westrope, Pleasant Ridge, Mich., assignor, by mesne assignments, to Reconstruction Finance Corporation, Detroit, Mich., a corporation of the United States

Application April 26, 1940, Serial No 331,858

10 Claims. (Cl. 16—86)

This invention relates to door checks and, in particular, to vehicle door checks for checking the swinging movements of a hingedly supported door.

One object of this invention is to provide a door check adapted to apply a different retarding force to the door in one direction of its movement than in the other direction thereof.

Another object is to provide a door check having cam means adapted to releasably hold the door in open position yet to tilt and release the door when a force is applied thereto in excess of a predetermined force.

Another object is to provide a door check having means associated therewith for applying a relatively slight retarding force to the door during its opening movement but a relatively great retaining force for holding the door in an open position.

Another object is to provide a door check having a yieldingly urged tiltable cam engaged by a projection on the door check link or strap to tilt the cam with a relatively slight retarding force during the opening movement of the door but to tilt the cam in the opposite direction with a relatively great retarding force resisting the closing movement of the door and releasably holding the door in its open position.

Another object is to provide a door check as set forth in the preceding objects wherein an abutment is also provided for bringing the door to a halt at the end of its opening movement.

Another object is to provide a door check as set forth in the preceding objects wherein the cam is urged into engagement with an opposing element of the door check by a spring member, such as a leaf spring or a coil spring.

In the drawings:

Fig. 1 is a top plan view, partly in section, showing one embodiment of the invention in the closed position of the door and with a cam having a coil spring for urging it into engagement with the door strap or link;

Fig. 2 is a vertical longitudinal section taken along the line 2—2 in Fig. 1;

Fig. 3 is a view similar to Fig. 1 but showing the door in its checked position at the end of its opening movement;

Fig. 4 is a vertical longitudinal section along the line 4—4 in Fig. 3;

Fig. 5 is a vertical cross section along the line 5—5 in Fig. 4;

Fig. 6 is a view similar to Fig. 4, but showing a modification having a tension adjustment for the cam urging spring;

Fig. 7 is a view similar to Fig. 4 of another modification having a leaf spring engaging the cam;

Fig. 8 is a vertical cross section along the line 8—8 in Fig. 7;

Fig. 9 is a view similar to Fig. 4 but showing a further modification having a hollow cam urged by coil springs;

Fig. 10 is a vertical cross section along the line 10—10 in Fig. 9;

Fig. 11 is a view similar to Fig. 10 but showing a modification wherein a block of resilient rubber-like material is employed in place of the coil springs;

Fig. 12 is a vertical cross section along the line 12—12 in Fig. 11;

Fig. 13 is a modification similar to Fig. 4 but having a shorter cam and coil spring;

Fig. 14 is a view similar to Fig. 4, but showing a modification having a pair of opposed cams engaging opposite sides of the door link or strap; and

Fig. 15 is a right hand end elevation of the device shown in Fig. 14, with the door link or strap in cross section.

In general the door check of the present invention consists of a strap or link having a projection engaged by a cam which is urged into engagement therewith by spring mechanism. This door check is so arranged as to retard the movement of a swinging door in a gradual manner so as to avoid damage to the door or body and at the same time releasably hold the door in an open position.

For this purpose the door check generally consists of a housing or retaining structure and a strap or link, one of these being attached to the door structure and the other to the body structure. The retaining structure or housing contains a tiltable cam engageable with a projection on the strap or link and having a spring member for maintaining this engagement. Optional means are provided for adjusting the tension of this spring member and other optional forms of springs are disclosed.

One characteristic of the invention is the provision of a door check which will exert a relatively slight retarding force upon the door structure during its opening movement but which will exert a relatively powerful retaining force to prevent the closing of the door and to releasably retain the door in its open position. This is accomplished by providing the tiltable cam with a high portion having a gradual approach on one side and an abrupt approach upon the other side,

these being preferably positioned to respectively engage abruptly and gradually inclined portions on the door link or strap.

Referring to the drawings in detail, Fig. 1 shows a supporting structure 10 and a door structure 11 mechanically connected by hinges 12 on hinge pins 13, one only of these hinges being shown. Secured as at 14 to the wall 15 of the structure 10 are angle members 16 projecting outwardly through an aperture 17 in parallel relationship. The angle members 16 collectively form a bracket, generally designated 18, and carrying a pivot pin 19 which pivotally engages the door link or strap 20. The latter is provided with a projection 21 having a gradually inclined portion 22 and an abruptly inclined portion 23, these being formed by upsetting a portion of the link 20 as at 24. This forms a projection on the one side of the link and a depression upon the other side thereof. The end of the link 20 is provided with a pin 25 engaged by a plate 26 serving as a backing for a resilient block 27 of rubber-like material.

Secured as at 28 to the wall of the door structure 11 is a retaining structure or housing 30 and a closure plate 31 therefor (Fig. 2). These are provided respectively with apertures 32, 33 and 34 through which the link 20 passes. The retaining structure 30 above the apertures 33 and 34 is provided with a curved bearing portion 35 engaged by the upper surface of the link or strap 20.

The underside of the link or strap 20 is engaged by a tiltable cam 36 having a high portion 37 with inclined approaches 38 and 49 on opposite sides thereof and with flattened portions 49 and 41 leading downwardly therefrom to a curved cylindrical portion 42 seated in a correspondingly curved cylindrical depression 43 in a block 44. The latter is provided with a stem 45 surrounded by a coil spring 46. One end of the coil spring 46 engages the lower wall 47 of the retaining structure or housing 30, whereas, the other end engages the block 44 to urge the cam 36 into engagement with the link 20, and particularly into engagement with the projections 21 thereon. The retaining structure or housing 30 is provided with a wall 48 adapted to be engaged by the flat portion 41 of the cam 36 when the latter is tilted to the right after the projection 21 passes by it as the door is swung into its open position (Figs. 2 and 3).

In the operation of the door check, with the door in its closed position (Figs. 1 and 2), the cam 36 is tilted into the position shown in Fig. 2 by the action of the coil spring 46. When the door structure 11 is opened, the strap or link 20 and the cam 36 move relatively to one another and the projection 21 slides over the cam 36 and drops into position upon the side thereof. The cushion block 27 then comes into engagement with the housing or retaining structure 30 and halts the opening movement of the door in the position shown in Figs. 3 and 4. The abruptly inclined portion 23 of the projection 21 is then in engagement with the portion 39 of the cam 36 and holds the door in its open position.

To close the door, a substantially powerful force must be applied thereto so as to force the projection 21 over the cam 36 while the latter is pushed downwardly against the urge of the coil spring 46 as it is being tilted to the right. When the cam 36 reaches its extreme right hand position, its flat surface 41 engages the inner surface of the wall 48 and slides thereon in

bearing engagement until the projection 21 rides over the high portion 37 of the cam and the parts move into the position shown in Fig. 2.

Thus, in the door check of this invention, a relatively slight retarding force is applied to the door when the gradually inclined portion 22 of the projection 21 rides over the cam 36 in one direction, whereas a much more powerful force is required to overcome the resistance in the opposite direction and force the abruptly inclined portion 23 of the projection 21 over the top 37 of the cam 36 and tilt the latter in the opposite direction.

The modification shown in Fig. 6 is similar to the form shown in Figs. 1 to 5, inclusive, except that the housing or retaining structure 30 is provided with a threaded portion 50 engaged by the corresponding threads 51 of an adjusting screw 52 having an enlargement 53 engaging the lower end of the coil spring 46. By turning the adjusting screw 52, the force of the coil spring 46 may be increased or decreased as desired.

The modification shown in Figs. 7 and 8 is generally similar to the form shown in Figs. 1 to 5, inclusive, except that a double leaf spring 61 is employed for urging the cam 36 upwardly into engagement with the strap or link 20. A flat spring 62 is also optionally employed in engagement with the upper surface of the strap or link 20.

In the modification shown in Figs. 9 and 10, the cam 36 is provided with hollow sockets 54 for receiving coil springs 55. The sockets 54 enter into a recess 56 in the form of a lateral groove (Fig. 10). The groove 56 serves to receive a pin 57 supported between the opposite walls of the housing or retaining structure 30.

In the operation of the modification shown in Figs. 9 and 10, the gradual incline 22 of the projection 21 rides easily over the gradually inclined portion 38 of the cam 36 and the abruptly inclined portion 23 snaps into the position of Fig. 9 over the high portion 37 and in engagement with the abruptly inclined portion 39 of the cam 36. The cushion block 27 then engages the housing 30 and brings the door structure 11 to a halt at the end of its opening movement. The door structure is thus held in its open position until a powerful force is applied, sufficient to push the projection portion 23 over the cam portion 39 and compress the coil springs 55 while pushing the cam 36 downwardly as it is tilted and swung to the right (Fig. 9). At the end of its tilting movement its outer side 41 slidably engages the inner wall 48 of the housing or retaining structure 30 (Fig. 9).

The modification shown in Figs. 11 and 12 is generally similar to that shown in Figs. 9 and 10 except that a block 58 of resilient or rubber-like material is inserted in a hollow recess 59 in the cam 36 in engagement with a bearing member 60 which in turn engages the cross pin 57. The operation of the modification of Figs. 11 and 12 is similar to that of Figs. 9 and 10.

The modification shown in Fig. 13 is similar to the form shown in Figs. 1 to 5, inclusive, except that the cam 36 is relatively shorter and is engaged by a hollow cap 63 partly surrounding the coil spring 46. The device is also provided with a wear plate 64 engaging the upper surface of the link or strap 20. The operation of this modification is similar to that of the form shown in Figs. 1 to 5, inclusive.

The modification shown in Figs. 14 and 15 employs a pair of cams 66 on opposite sides of

the link or strap 20, and engageable with a pair of projections 21 similar to those already described by projecting in opposite directions. The cams 66 are urged toward the link or strap 20 by multiple leaf springs 67 extending transversely of the retaining structure or housing 68.

The cams 66 are of polygonal cross section and having flat sides 69, 70, 71, 72, 73 and 74 together with a rounded high portion 75 engageable with a projection 21 on the link or strap 20.

In the operation of the modification shown in Figs. 14 and 15, the opening of the door causes the projections 21 to slip past the cams 66 into the position shown in Fig. 14, and the cushion block 27 brings the door to a halt. The door is held in its open position by the engagement of the abruptly inclined portions 23 of the projections 21 with the aforesaid portions 73 of the cams 66 until a force is applied which is sufficient to overcome the thrust of the multiple leaf springs 67. When this occurs, the cams 66 are tilted to the right and forced outwardly in opposite directions away from each other, compressing the springs 67. When the cams 66 reach their extreme right hand positions, their flattened portions 71 engage the adjacent inner walls of the housing or retaining structure 68 and slide relatively thereto as the springs 67 are compressed. After the projections 21 pass over the peaks or high portions 75 of the cams 66, the latter are pushed toward each other by the multiple springs 67 until they again assume the positions of Fig. 14, but with the projections 21 now on the right hand side thereof.

While a specific embodiment of the invention has been described and illustrated, it will be understood that various modifications may be made within the scope of the appended claims without departing from the spirit of the invention.

What I claim is:

1. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, tiltably movable cam means pivotally mounted in said retaining means, means for restricting the motion of said cam means to a path to and fro along the path of said elongated member, spring means for urging said cam means into engagement with said elongated member, and means on said elongated member spaced apart from said abutment and engageable with said cam means to tilt said cam means to and fro in response to the motion of said elongated member for releasably holding the door structure in an open position, said cam means having a high portion with a gradual approach on one side thereof.

2. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, tiltably movable cam means pivotally mounted in said retaining

means, means for restricting the motion of said cam means to a path to and fro along the path of said elongated member, spring means for urging said cam means into engagement with said elongated member, and means on said elongated member spaced apart from said abutment and engageable with said cam means to tilt said cam means to and fro in response to the motion of said elongated member for releasably holding the door structure in an open position, said cam means having a high portion with a gradual approach on one side thereof and an abrupt approach on the other side thereof.

3. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, cam means associated with said retaining means, spring means for urging said cam means into engagement with said elongated member, means on said elongated member spaced apart from said abutment and engageable with said cam means for releasably holding the door structure in an open position, and bearing means disposed between said cam means and said spring means for tiltably receiving and supporting said cam means.

4. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, cam means associated with said retaining means, spring means for urging said cam means into engagement with said elongated member, and means on said elongated member spaced apart from said abutment and engageable with said cam means for releasably holding the door structure in an open position, said retaining means having a bearing portion thereon and said cam means having a co-operating bearing portion slidably engageable with said retaining means bearing portion in response to the shifting of said cam means.

5. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, cam means associated with said retaining means, spring means for urging said cam means into engagement with said elongated member, and means on said elongated member spaced apart from said abutment and engageable with said cam means for releasably holding the door structure in an open position, said retaining means having a bearing portion thereon and said cam means having a co-operating bearing portion slidably engageable with said retaining means bearing portion in response to the shifting of said cam means, and

said cam means having a high portion with a gradual approach on one side thereof.

6. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, cam means associated with said retaining means, spring means for urging said cam means into engagement with said elongated member, and means on said elongated member spaced apart from said abutment and engageable with said cam means for releasably holding the door structure in an open position, said retaining means having a bearing portion thereon and said cam means having a cooperating bearing portion slidably engageable with said retaining means bearing portion in response to the shifting of said cam means, and said cam means having a high portion with a gradual approach on one side thereof and an abrupt approach on the other side thereof.

7. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, cam means associated with said retaining means, spring means for urging said cam means into engagement with said elongated member, and means on said elongated member spaced apart from said abutment and engageable with said cam means for releasably holding the door structure in an open position, said cam means having a hollow recess for receiving said spring means therein.

8. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening move-

ment of the door structure, cam means associated with said retaining means, spring means for urging said cam means into engagement with said elongated member, means on said elongated member spaced apart from said abutment and engageable with said cam means for releasably holding the door structure in an open position, said cam means having a hollow recess thereacross for receiving said spring means, and a supporting member in said recess in engagement with said spring means.

9. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, cam means associated with said retaining means, spring means for urging said cam means into engagement with said elongated member, means on said elongated member spaced apart from said abutment and engageable with said cam means for releasably holding the door structure in an open position, said cam means having a hollow recess thereacross for receiving said spring means, and a supporting member in said recess in engagement with said spring means, said supporting member being mounted in said retaining means and extending thereacross.

10. In a door check for checking the opening movement of a door structure and for releasably holding the door structure in an open position relatively to a supporting structure, retaining means associated with one of said structures, an elongated member associated with the other of said structures and extending through said retaining means, an abutment on said elongated member positioned to halt the opening movement of the door structure, cam means associated with said retaining means, resilient means for urging said cam means into engagement with said elongated member, and means on said elongated member spaced apart from said abutment and engageable with said cam means for releasably holding the door structure in an open position, said cam having a hollow recess therein for receiving said resilient means.

FREDERICK J. WESTROPE.
